JPO Design Division Prior Art Ref. No. HA 15021476 disclosed on page 122 of GOGGLE vol. 11, dated Nov. 1, 2003, which is furnished in the National Center for Industrial Property Information on Sep. 25, 2003.

Primary Examiner—Ruth McInroy

(74) Attorney, Agent, or Firm—Karl G. Hanson

(57) **CLAIM**

The ornamental design for a welding helmet visor, as shown and described.

DESCRIPTION

FIG. 1 is a perspective view, showing the new design for a welding helmet visor;

FIG. 2 is a left side view, the right side view being a mirror image thereof;

FIG. 3 is a top view thereof;

FIG. 4 is a front view thereof;

FIG. 5 is a bottom view thereof; and,

FIG. 6 is a rear view thereof.

The broken lines form no part of the claimed design, and the shading is provided to illustrate contour only and is not an indication of texture, gloss, etc.
